UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

STEEL BODY FOR AUTOMOBILES.

Application filed November 6, 1919. Serial No. 336,059.

To all whom it may concern:

Be it known that I, JOSEPH LEDWINKA, a citizen of the United States, residing at Philadelphia, county of Philadelphia, State 5 of Pennsylvania, have made a certain new and useful Invention in Steel Bodies for Automobiles, of which the following is a specification.

This invention relates to automobile 10 bodies, and particularly structures of this class built up of sheet steel stamped or otherwise formed into the desired shape and contour and secured together to make up the complete body.

15 The object of the invention is to provide a structure of sheet steel automobile body which is simple, strong and rugged, and which can be easily, quickly and economically manufactured.

20 A further object is to provide a tonneau body panel having means formed therein to support the seat.

A further object is to provide a novel 25 construction for the vertical front edges of the tonneau which shall be particularly strong and rigid and provide an efficient support for the side door.

30 A further object is to provide a front seat panel having integral vertical front edge extensions of channel formation to form efficient front door posts.

A further object is to provide a rear 35 vertical edge structure of cowl panel to form an efficient door post.

40 A further object is to provide a door hinge support structure in the door posts of such arrangement as to afford a brace for the post structure.

A further object is to provide means for 45 reinforcing and stiffening the upper edge of the tonneau panel.

A further object is to provide a body structure in which interiorly extending door posts are avoided, thereby increasing 50 the floor space or area in the interior of the body.

A further object is to provide a single 55 self contained sheet metal body structure which includes, contains and combines these several advantageous features in a unitary structure.

Other objects of the invention will appear more fully hereinafter.

The invention consists substantially in

the construction, combination, location, and 55 relative arrangement of parts, all as will be more fully hereinafter set forth, as shown in the accompanying drawings, and finally pointed out in the appended claims.

Referring to the accompanying drawings,

Fig. 1 is a view in side elevation of the tonneau portion of an automobile body constructed in accordance with and containing features embraced within the scope of 65 my invention.

Fig. 2 is a similar view of the tonneau panel.

Fig. 3 is a top plan view of a side portion of the tonneau panel shown in Fig. 2. 70

Fig. 4 is a front elevation of the portion of tonneau panel shown in Figs. 2 and 3.

Fig. 25 is a broken view in vertical section similar to Fig. 23 through the front door post.

Fig. 26 is a detached detail view of the cushion retaining strip for the front seat.

Fig. 27 is a front view of the same.

Fig. 28 is a side view of the same.

Fig. 29 is a detached detail view of the threshold strip for the front door opening.

Fig. 30 is a front view of the same.

Fig. 31 is a cross section on the line 31, 31, Fig. 29.

Fig. 32 is a detached detail view in side elevation of the rear door opening threshold strip.

Figs. 33 and 34 are sections on the lines 33, 33, and 34, 34, respectively, of Fig. 32.

Fig. 35 is a front view of the strip shown in Fig. 32.

Fig. 36 is a detached detail view in side elevation of the toe board support.

Figs. 37 and 38 are, respectively, a front view and a top view of the same.

Fig. 39 is a section on the line 39, 39, Fig. 38.

Fig. 40 is a view in side elevation of the cowl portion of the body embodying my invention.

Fig. 41 is a view partly in side elevation and partly in vertical section showing the windshield supporting bracket structure.

Fig. 42 is a section through the same on the line 42, 42, Fig. 41.

Fig. 43 is a broken view in vertical transverse section through the rear doorway on the line 43, 43, Fig. 1.

The same part is designated by the same reference numeral wherever it occurs throughout the several views.

In the manufacture of automobile bodies it is desirable to secure strength and rigidity in the completed structure, simplicity in the parts composing the structure, and speed in the assembling and joining of the parts together, in order to secure economy. In at-

taining this result it is equally desirable to secure ruggedness in the completed structure and the production of a body which is capable of efficiently withstanding the shock, jars, and vibration in use.

In the accomplishment of these objects and purposes I propose to construct the automobile body out of sheet steel stampings which are pressed or stamped into the desired shape and contour and are assembled and secured together to produce a single integral homogeneous structure.

Referring to the drawings, and particularly to Figs. 1, 2, 3, 4 and 6, the tonneau is formed of sheet steel stampings 50 which are pressed into the desired contour and shape to form the sides and back of the rear seat portion of the body. In forming the stamping panel 50 a lateral inset depression 51 is formed in the sides thereof to constitute a housing or space in which the automobile wheel operates. An auxiliary inwardly extending depression or seat indicated at 52 is also pressed into the side portion of the panel 50 and in the depressed or inset portion 51 thereof, to form a ledge or shoulder 53, see Figs. 4 and 6, to receive and form a rest for the side edge of the seat pan 54. The rear edge of the seat pan rests upon a strip or stamping indicated in dotted lines at 55 in Fig. 1 which is secured to the interior surface of the panel stamping 50 and is provided with a shoulder portion 56 upon which the rear edge of the seat pan rests.

A bracket member indicated generally at 57, Figs. 16 and 17, and in dotted lines in Fig. 1, is formed with the vertical portion 58, which is U-shaped in cross section as seen in Fig. 18, with a longitudinally extending portion 59 and with a transversely extending portion 60, the former being angle shaped in cross section as shown in Fig. 19, the longitudinal sill member of the frame indicated at 61 see Fig. 5^a, receiving the longitudinally extending portion 59 of the bracket. The front edge of the tonneau stamping 50 is secured to the vertical portion 58 of the bracket and a bracing cross member 62 see Fig. 1 is connected to the laterally extending portion 60 of the bracket. This forms an exceedingly simple and strong connection for bracing the body structure and securing the same to the frame sills, the bracket portion 59 having considerable length for efficient securing to the frame sill. Thus the opposite sides of the body are efficiently tied together by the cross member 62 attached at its ends to the lateral extensions 60 of the brackets.

A stamping indicated at 63 disposed in a vertical plane and extending transversely across the tonneau panel at the front edge of the seat and secured at its ends to the vertical portion of the auxiliary seat or depression 52 at the forward extremity of

- the latter, or the front wall of said auxiliary depression, constitutes a heel board for the rear seat of the body, this panel 63 being formed with a shoulder 64 adjacent its upper edge upon which the front edge of the seat pan is supported. Forward of the shoulder 64 the heel board panel 63 is flanged upwardly as at 65 to extend slightly above the seat pan to form a ledge for retaining the seat cushion in place. The heel board 63, if desired, may be formed with a depression 67 in the vertical face thereof, as shown in Fig. 6, in order to stiffen the same. The lower edge of the body panel 50 is flanged inwardly, see Fig. 5 as indicated at 68, to form a support for the edge of a floor panel 69. If desired, this floor panel may be suitably corrugated as indicated at 70 to stiffen the same.
- 20 In the structure above described, the bracket members 57 reinforce and strengthen the forward edges of the tonneau panel, and take the place of the usual door posts, affording sufficient strength and rigidity at the forward vertical edges of the tonneau to enable the structure to take the shocks and stresses usually imposed on door posts. These bracket members, however, extend partway towards the top edge of the tonneau panel, and they do not extend substantially into the interior space of the tonneau as is the case with the usual door post structures. The result is that I am enabled to increase the interior area of the tonneau, making the same large and roomy without increasing the transverse dimension of the body.
- 25 The front seat panel or stamping is indicated generally at 66, Figs. 7, 8, 11 and 12, and is suitably shaped and formed into the desired contour. In practice I prefer to form this panel in two sections 71 and 72, see Figs. 7 and 8, suitably joined together at their adjacent edges as indicated at 73. By this structure one of the portions 71, 72, of said panel, may be of thicker and heavier material than the other, thereby securing strength and rigidity. In practice the upper portion 72 is made thicker than the lower portion for this purpose. The upper edge of 30 the panel 66 is flanged inwardly as indicated at 74, as is likewise the upper edge of the tonneau panel 50, and an angle strip 75 is applied to the inturned flange 74, thus forming a channel along the upper edge of 35 the panels 50, 66, to afford means for securing suitable cushions or upholstery.
- 35 The ends of the front seat panel 66 are pressed into channel form with the open side thereof presenting inwardly as indicated at 76, see Fig. 10, thus forming the door posts integrally with the panel.
- 40 If desired, suitable depressions 77, 78, may be formed in the front seat panel 66 or the rear portion thereof to stiffen the same, and, 45 if desired, the depression 77 may be employed to receive the robe rail supports. To this end the depression 77 is formed horizontally across the back of the front seat panel and is enlarged at its ends as indicated at 79, Fig. 11, robe rail supporting brackets 70 of the usual character (not shown), being received in these enlarged depressions 79. At its lower edge the front seat panel is formed with a rearwardly extending flange 80 to be secured to any suitable cross brace 75 of the frame. Extending transversely across the front seat panel is the front seat heel board indicated at 82, see Figs. 7, 13, 14. If desired, the side portions of heel board 82 may be formed with central depressions 83 on their outer faces as indicated at 88, see Fig. 14, for stiffening purposes. In the form shown, to which, however, my invention is not to be limited, the front seat heel board, 82, has its ends extending rearwardly to form the side portions of the heel board, as shown in Figs. 7 and 14. A laterally extending flange, 86, is formed at the upper edge of this heel board to support the front seat pan, 84, and the retainer strip, 121, for the front seat cushion, shown in Figs. 26, 27, and 28, is secured in any suitable manner to the flange 86.
- 45 The front seat pan indicated at 84, Fig. 7, is supported at its rear edge upon a stamping 85 and at its front edge upon a shoulder 86 formed at the upper edge of the heel board 82, the latter, if desired, being formed with a depression 87 for stiffening purposes.
- 50 Suitably mounted within the door posts 76 are blocks 88 which serve the double purpose of bracing the channel formed along the vertical edges of the front door panel to constitute the door post and also to receive and support the pivot arms 89 of the rear door 90, see Figs. 23 and 24. A stamping 91 is applied to the inner open edge of the channel post to form a hinge house to enclose the hinge structure for the rear door. The front door 92 closes upon the forward outer corner of the channel door post. If desired, a border strip 93 of angle shape in cross section, see Figs. 21, 24, 29 and 31 is applied to the forward flat side of the front seat panel or rather to the front flat side of the channel formed in the front vertical edge of the front seat panel, and this border strip extends over the inturned flange 94 of the body panel portion 95 to form a threshold strip. The body panel portion 95 is flanged inwardly as at 96 and then upwardly as at 97 over the frame sill 61 and then is inturned as at 98 to form a shoulder upon which rests the floor board 99, see Figs. 21 and 22.
- 55 In Fig. 40 I have shown the cowl panel 100 which is formed with an inturned flange 101 at its forward edge. To this flange is secured a sheet steel panel 102. To this

panel 102 is secured the forward end of a bracket 103. The rear end of this bracket has attached thereto a bracket stamping 104 which embraces the windshield stanchion 105, said stanchion extending vertically through the seating formed in the stamping 104 and being clamped thereto by means of a nut 106. The cowl stamping 100 also embraces the windshield stanchion 105 and 10 reinforcing angle plates 107 serve to reinforce the connection between the cowl stamping and the windshield stanchion and that part of the cowl beneath the lower edge of the windshield. A stamping 108 15 is flanged at its upper edge to fit between the rear edge of the cowl stamping and the reinforcing angle plates 107. This plate 108 extends transversely across the body and is attached by means of angle plates 109 to an angle shaped stamping 111 constituting a door post cap at the rear vertical edge of the cowl and to which the inturned flange 112 of the cowl stamping 20 is secured. The panel 108 constitutes the instrument board on which are mounted the usual indicators, clock, lighting and starting switches, etc.

The bracket stamping 104 is secured to a vertical inturned flange 110 of the angle 25 post 111.

It will appear from the foregoing that the braces, one at each side of the cowl made up of the brackets 103 and 104, serve a double function in that they brace the cowl longitudinally and serve as supports or anchors for the windshield stanchions.

In connection with Fig. 22 I have described the flooring 99 as resting upon a flange 98 of the portion 95 of the body stamping. 30 The door sill strip 93 in this arrangement forms an abutment against which the outer edge of the flooring 99 abuts. If desired, however, this abutment may be formed by offsetting a flange portion 112 of the door sill or strip 119, as seen in Fig. 43, and the floor board 113 rests at its edge upon the depressed or offset flange 112 and abuts against the shoulder formed thereby and also rests upon the flange 98.

35 The form of door strip 93 is shown more in detail in Figs. 29, 30 and 31. This is simply a stamping L-shaped in cross section, having preferably a rounded outer edge as at 118, and formed in generally rectangular shape to fit the front door opening. The door strip for the rear door opening is shown at 119, see Figs. 32, 33, 34, 35. The vertical portions of this strip are preferably of L-shape in cross section, see Fig. 33, with a rounded outer edge 120. The horizontal portion of the border strip 119 is likewise formed with a rounded outer edge 120, but instead of being L-shape it is formed with a depressed flange 112, see 40 Figs. 34 and 43.

Suitably mounted within the cowl is the usual toeboard. The toe board is suitably supported at its ends upon supporting stampings 122. A toe board supporting stamping is applied inside the cowl panel at 45 opposite sides thereof, and is formed with the usual inclined surface against which the ends of the toe board are supported in the usual inclined relation. From the foregoing description it will be seen that I provide 50 standard stamping for the various parts going to make up a complete sheet steel body for automobiles. These stampings are made of standard sizes and produced rapidly in quantities. The various stampings forming the complete body are then assembled 55 and welded or otherwise secured together, thus forming an integral homogeneous completed body in which the various parts or stamping brace each other, thus forming an exceedingly strong and rugged structure and enabling me to produce sheet steel bodies rapidly and economically and of all 60 steel stampings.

Having now set forth the objects and nature of my invention and a construction embodying the principles thereof, what I claim as new and useful and of my own invention and desire to secure by Letters Patent is,—

1. In a sheet metal automobile structure, a stamping shaped to form the side and back portions of a seat, the side portions of said stamping having inwardly pressed portions forming ledges or shoulders to support a seat pan, and a vertically disposed heel board at the front edge of said seat secured at its ends to said inwardly pressed portions of the stamping.

2. In a sheet steel structure for automobile bodies, a sheet steel stamping shaped to conform to the contour and outline of the body, and having a depressed portion in the side thereof to form a wheel housing and an auxiliary depression stamped in the wheel housing to form a seat support.

3. In a sheet steel structure for automobile bodies, a sheet steel stamping shaped to conform to the contour and outline of the body, and having a depressed portion in the side thereof projecting into the interior of the body to form a ledge or shoulder to receive a seat pan.

4. In a sheet metal body structure for automobiles, a panel curved to form the sides and back of a seat, a reinforcing member having a vertically-extending portion, a longitudinally-extending portion and a transversely-extending portion, said vertically-extending portion being secured to a vertical front edge of said panel, a body sill connected to said longitudinally-extending portion, and a cross member connected to said transversely-extending portion.

5. In a sheet metal body structure for automobiles, a panel curved to conform to

- the body curvature and forming the sides and back of a seat, a reinforcing member having a pair of horizontal portions extending at right angles to each other and a vertical portion which is curved to conform to the body curvature and engages and is secured to a front vertical edge of said panel, a body sill, and a cross member, each connected to one of said horizontal portions.
10. In a sheet metal body structure for automobiles, a tonneau panel curved to form the sides and back of a rear seat, a pair of reinforcing members secured to the lower forward portions of the tonneau panel, and a pair of body sills, one at each side of the body, each sill having its rear end connected to one of said reinforcing members.
15. In a sheet metal body structure for automobiles, a tonneau panel curved to form the sides and back of a rear seat, a pair of reinforcing members secured to the lower forward portions of the tonneau panel a cross member connecting said reinforcing members, and a pair of body sills, one at each side of the body, each body sill having its rear end connected to one of said reinforcing members.
20. In a sheet metal body structure for automobiles, a tonneau panel curved to form the sides and back of a rear seat, and a pair of body sills extending longitudinally of the body, one at each side thereof, the rear ends of said body sills terminating at and connected to the lower forward portions of the tonneau panel.
25. In a sheet steel structure for automobile bodies, a sheet steel seat panel shaped to conform to the contour and outline of the front seat, the front vertical edges of said panel being, respectively, bent into channel formation to form a door post structure.
30. In a sheet steel structure for automobile bodies, a sheet steel seat panel shaped to conform to the contour and outline of the front seat, the front vertical edges of said panel being, respectively, bent into channel formation to form a door post structure, and door hinge supporting members housed within and forming a brace for said channel post.
35. In a sheet steel structure for automobile bodies, a sheet steel panel shaped to conform to the contour and outline of the front seat, said panel having depressions formed therein, in the seat back portion thereof adapted to stiffen the same and to receive and position robe rail supports.
40. In a sheet steel structure for automobile bodies, a sheet steel panel shaped to conform to the contour and outline of the body, in combination with a longitudinally extending frame sill member, the lower edge of said panel being bent inwardly beneath and upwardly against said sill member, and terminating in an inturned flange, and a
- floor member supported by said inturned terminal flange.
45. In a sheet steel structure for automobile bodies, a sheet steel panel shaped to conform to the contour and outline of the body, and having a door opening formed in the side thereof, in combination with a border strip for said door opening, said strip extending along a vertical side and bottom of said opening, said border strip being formed with a downwardly depressed inner edge to form a supporting shoulder, and a floor panel supported at its edge upon said shoulder the flooring abutting at its edge against said border strip.
50. In a sheet steel structure for automobile bodies, a sheet steel panel shaped to conform to the contour and outline of the body, said panel having an opening in the side thereof to form a doorway, the edges of said panel bordering said opening being turned inwardly, and a border strip for said opening, said border strip secured to said inturned flanges, said border strip having an inwardly extending portion at the threshold portion of the doorway, and a floor panel supported on said inwardly extending portion.
55. In a sheet steel structure for automobile bodies, a sheet steel panel shaped to conform to the contour and outline of the cowl, in combination with auxiliary stampings mounted upon and secured to the inner side walls of said panel, and having inclined upper edges to form a support for the ends of the toe board.
60. In a sheet steel structure for automobile bodies, a sheet steel panel shaped to conform to the contour and outline of the cowl, in combination with auxiliary stampings having angle-shaped longitudinally-extending portions and inclined upper edges, said auxiliary stampings being rigidly secured directly to the interior surfaces of the side walls of said panel.
65. In a sheet steel structure for automobile bodies, a sheet steel panel shaped to conform to the contour and outline of the cowl, channel shaped members secured to the rear vertical edges of said panel to form door posts, brackets secured to said door posts, and windshield stanchions carried by said brackets, said brackets forming the sole support for said stanchions.
70. In a sheet steel structure for automobile bodies, a sheet steel panel shaped to conform to the contour and outline of the cowl, channel shaped members secured to the rear vertical edges of said panel to form posts, brackets secured to said posts, windshield stanchions mounted in said brackets, and an instrument panel supported at its upper edge upon said stanchions and connected at its lower edge to said posts.
75. In an automobile body structure, a

cowl structure, in combination with a brace secured at its ends to the forward and rear portions of the cowl structure, respectively, to reinforce and brace the latter, said brace 5 also forming a windshield support.

20. In an automobile body, a cowl structure including a cowl panel, a transverse panel secured to the forward edges of said cowl panel and reinforcing members secured to the rear edges of said cowl panel in combination with a brace at each side of the cowl structure, said braces connected, at their forward ends, to said transverse panel and, at their rear ends, to 15 said reinforcing members, said braces being provided with means for receiving and supporting the windshield stanchions.
21. In a sheet steel structure for automobile bodies, a body side panel shaped to the

contour and curvature of the body and having a door opening formed therein, in combination with a border strip for the door opening, said strip extending along a side and bottom of said opening, and having its inner lower edge bent downwardly and thence inwardly to form a supporting shouldered ledge and a floor panel supported at its edge upon said ledge.

22. In a motor vehicle, the combination with the pillar and the dash, of a supporting bracket rigidly connected to the dash and to the pillar and having a socket member to receive a part of the windshield.

In testimony whereof I have hereunto set my hand on this 23rd day of October, A. D. 35 1919.

JOSEPH LEDWINKA.
